(57) **CLAIM**

The ornamental design for a power meter, as shown and described.

DESCRIPTION

FIG. 1 is a front, top, left perspective view of a power meter that can be optionally connected to a DIN rail or a display module;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of structural features is included for the purpose of illustrating non-claimed subject matter and forms no part of the claimed design.

1 Claim, 7 Drawing Sheets
